PERMEABILITY TUNED IMAGE ATTENUATION CIRCUITS

William Francis Sands, West Collingswood, N. J., assignor to Radio Corporation of America, a corporation of Delaware

Application December 30, 1942, Serial No. 470,543

4 Claims. (Cl. 250—20)

1

The present invention relates to image attenuation circuits in superheterodyne receivers, and more particularly to such circuits utilizing permeability tuning.

It is well known that the superheterodyne type of receiver is susceptible to the reception of an undesired or interfering frequency along with the desired signal frequency for each setting of the receiver tuning means. The undesired frequency is commonly referred to as the "image frequency" and is removed from the desired signal by twice the value of the intermediate frequency. This is because for each value of the local oscillator frequency, there are two frequencies which are spaced one above and the other below the oscillator frequency by the amount of the intermediate frequency, each of which heterodynes with the local oscillator frequency to produce the same intermediate frequency. Various schemes have been devised for the suppression or attenuation of the image frequency.

In accordance with the present invention, there is provided between the antenna or signal collector and the first tube of the receiver, or between two successive tubes, a coupling system functioning as a band pass network so designed as to effect maximum transmission at the desired frequency and to provide maximum attenuation to the interfering image frequency.

Briefly, the invention contemplates the use, in conjunction with a permeability tuned signal frequency circuit of a superheterodyne receiver, of a low impedance winding in coupled relation with the inductance winding of the signal circuit and a capacitor connected between the high potential ends of said windings. The mutual inductance between the windings is made of such magnitude and sign that together with the capacitor a parallel trap circuit is formed which rejects the image frequency. By having the low impedance winding wound coaxially and substantially coextensively over a greater portion or the entire length of the main tuning coil and with a varying pitch, the rejection of the image frequency is made to follow or "track" the tuning of the receiver across the signal frequency band. In order that the image rejection may be made substantially infinite a resistance cancellation element is employed (as shown by H. W. Bode, U. S. Patent No. 2,002,216) to balance out the energy dissipation in the rejector circuit.

It is one of the main objects of the present invention therefore to provide simple signal frequency circuits, for use in broadcast or short-wave permeability tuned receivers, having sub-

2

stantially infinite image attenuation without causing disturbance to the normal receiver alignment, and such that the point of substantially infinite attenuation remains "tracked" with the tuning of the receiver across the entire tuning range.

Another object is to provide a permeability tuned loop antenna circuit having almost infinite image attenuation.

These and other objects and advantages will be apparent from the following specification, when taken with the accompanying drawing, in which

Fig. 1 discloses a permeability tuned signal frequency circuit in accordance with the invention providing image frequency attenuation.

Fig. 2 shows the circuit of Fig. 1 except that the permeability tuned circuit has been replaced by its electrical equivalent π -network.

Fig. 3 is a circuit embodying the principle of image rejection utilized in Fig. 1 but employing two permeability tuned circuits coupled by means of a link circuit.

Figs. 4 and 5 are image attenuation circuits in accordance with the invention for use with a loop antenna, and

Fig. 6 shows attenuation curves obtained with the networks of the invention, with and without the use of a resistance cancellation element.

Referring now more particularly to Fig. 1 the coil winding L_2 and its shunt capacitor C_4 constitute the signal frequency input circuit for the first tube T of the receiver which may be a radio frequency amplifier or a detector oscillator. The input circuit is tunable over its frequency range by means of ferromagnetic core means such as an iron core K movable within the coil L_2 in a known manner. A low impedance winding L_1 of relatively few turns is wound coaxially over the coil L_2 and in the same direction but with a relatively different distribution of turns along the path of said core means. Preferably the coil L_1 is wound with varying pitch, extending over the entire length of the coil L_2 or only over a substantial part thereof. The two windings which in effect constitute a transformer, with L_1 as the primary and L_2 as the secondary, have their low radio frequency potential ends connected together and which may be connected directly to ground or through a variable resistance r . The high radio frequency potential ends of the windings have connected between them an adjustable capacitor C_3 . The received signal energy which may be derived from an antenna A , or from a preceding radio frequency amplifier tube (not

shown), is fed to the high side of the primary L_1 by way of the coupling capacitor C_1 . If desired, the shunt capacitor C_2 may be employed to tune the primary somewhat above the frequency band of the receiver and to form with the condenser C_1 a capacitive voltage divider from which the signal energy is fed to the primary L_1 .

An important feature of spreading the relatively few turns of coil L_1 over the length of coil L_2 or a greater portion thereof is that the normal alignment of the input circuit with the other tunable circuits of the receiver at the signal frequency is not materially disturbed, as would be the case if the turns of coil L_1 were closely wound at one end, for example, the low potential end, of the secondary L_2 . By varying the pitch of L_1 , it is possible to keep the point of rejection "tracked" across the entire range. By way of example: for a signal frequency range of 6-18 mc. (i. e., 3:1) the image frequency would only vary from 6.91-18.91 mc., or a ratio of 2.74:1, and a slight amount of "slowing up" in the pitch is required. The foregoing has been based on the assumption of equal coil diameters for the signal and image frequency windings. In actual practice, the coil L_1 would be wound over, and spaced from, the secondary L_2 and some of the required "slowing up" would be secured also by this means. The series resistor r , in the circuit, may be adjusted for cancellation of dissipation in the mutual element, as described in the above mentioned Bode patent.

The above described coupling network of Fig. 1 may be resolved into its equivalent π network shown in Fig. 2 which is of the general form of band-pass networks with one point of infinite rejection, which in accordance with the present invention is tuned simultaneously with the tuning of the signal frequency circuit. The series arm of the π network is constituted by a parallel resonant circuit S which includes the capacitor C_3 and an inductance having the value

$$\frac{L_1 L_2 - M^2}{M}$$

the latter existing by virtue of the mutual inductance between the windings L_1 and L_2 . The magnitude and sign of the series inductive arm of the equivalent network, and the value of capacitor C_3 , are such that the circuit S is tuned to the image frequency ($f_s + 2$ I. F.) at any position of adjustment of the tuning core K . It is necessary that the inductance

$$\frac{L_1 L_2 - M^2}{M}$$

be physically realizable at all points in the tuning range or band, i. e., be of positive sign. This may be accomplished, most desirably, by winding L_1 and L_2 coaxially and in the same direction, and connecting the capacitor C_3 across the adjacent or high potential terminals of the windings as shown by Fig. 1, which represents the actual physical arrangement of transformer terminals. The shunt arms of the π network are constituted by the equivalent inductances

$$\frac{L_1 L_2 - M^2}{L_2 - M}$$

and

$$\frac{L_1 L_2 - M^2}{L_1 - M}$$

as indicated by Fig. 2.

By virtue of the coaxial arrangement of the two windings, and the variation of the pitch of

the primary along the length of the secondary, the inductance of the rejector or trap circuit S is varied in the proper sense with adjustment of the tuning core so that the rejection of the image signal is "tracked" across the entire tuning range.

A modification of the circuit of Fig. 1 is shown in Fig. 3 which has the advantage that additional adjacent channel selectivity is obtained. The essential difference is the use of two permeability tuned transformers T_1 and T_2 of generally similar construction as the transformer of Fig. 1, with their primaries L_1 connected together to form a link coupling circuit. Each primary L_1 is suitably spaced in a radial direction from its corresponding secondary L_2 and is wound with the proper variation in pitch to secure "tracking" of the image frequency. The coil L_2 of the first transformer T_1 together with the antenna capacity C' , the coupling capacitor C_1 and the shunt capacitor C_5 form a circuit which is tuned by means of the core K across the desired signal frequency range. Similarly, the coil L_2 of the second transformer T_2 together with the shunt capacitor C_4 form a circuit which is tuned by means of its core K across the same frequency range. The coupling circuit of Fig. 3 may be resolved into its equivalent π network which would be of the same form as shown in Fig. 2 except for different values of the series and shunt arms. The value of the series arm would be positive and equal to

$$\frac{2L_2(L_1 L_2 - M^2)}{M^2}$$

which together with the condenser C_3 effectively in parallel therewith form an image rejector circuit.

In the embodiment of Fig. 3, the coils L_1 and L_2 are shown to be wound in the same direction. Substantially similar results will be obtained if for both transformers the coils L_1 and L_2 are wound in opposite directions. The important consideration is that the same arrangement be used for both transformers. The reason for this may be readily seen from the fact that when one transformer is wound with L_1 in the same direction as L_2 and the other transformer with L_1 and L_2 wound in opposite directions, then the series arm of the equivalent π network, for the two transformers, is of negative sign, i. e.,

$$\frac{2L_2(L_1 L_2 - M^2)}{M^2}$$

For either of the preferred arrangements, stated previously, the series arm of the equivalent π network for the two transformers is of positive sign. A third possible combination is that in which the primary of one transformer is wound in the same direction as its secondary, and the primary of the other transformer is wound opposite to its secondary. The proper sign for the inductance element of the image trap is secured by reversal of the leads of one of the L^1 link windings.

An adaptation of the image suppression circuit of Fig. 1 to a loop antenna is shown in Fig. 4. Similar elements in both figures are designated by like reference characters. The high potential side of loop L_1 is connected directly to the high side of the primary L_1 which is chosen of such value to secure either an optimum, or a fairly uniform, transfer of voltage across the tuning range, as desired. The method of operation of the circuit of Fig. 4 is otherwise the same as that of Fig. 1. The circuit of Fig. 5 differs from that

of Fig. 4 in the respect that the resistance cancellation element r is connected between the low sides of the windings and ground.

In the case where it is desired to obtain a fairly large, but not substantially infinite, value of image attenuation (α), the resistance cancellation element r may be omitted, wherever shown. In Fig. 6 there is roughly shown by the solid line curve I the substantially infinite attenuation obtained where the resistance cancellation principle is employed, and by the dashed line curve F the large but entirely finite attenuation secured when the resistance cancellation element is omitted.

While I have shown and described certain preferred embodiments of the invention, it will be understood by those skilled in the art that modifications and changes may be made without departing from the spirit and scope of the invention.

What I claim is:

1. An input system for a superheterodyne radio receiver tunable over a range of frequencies and adapted when tuned to receive any desired signal frequency within said range to suppress a corresponding image frequency, said system comprising first and second coupled inductance windings having their low radio frequency potential terminals connected together and to ground, said windings being wound coaxially in the same direction to substantially the same length and having inductances L_1 and L_2 , respectively, and a mutual inductance M , said first winding having a varying distribution of turns along said winding, capacitance means in shunt with the second of the windings forming therewith a resonant circuit, a ferromagnetic core movable in a path with respect to said windings for tuning the circuit to said desired signal frequency, and series capacitance means including a capacitor connected between the high potential terminals of said windings forming with the inductance of the series arm of the equivalent π network for the pair of windings a rejector circuit which, by reason of said distribution of turns, is tuned at each core adjustment to the corresponding image frequency, said inductance having a value of

$$\frac{L_1 L_2 - M^2}{M}$$

throughout said range.

2. A circuit in accordance with the invention defined in claim 1 wherein the low potential terminals of the windings are connected to ground through resistance means which serves to reduce the energy dissipation in the rejector circuit.

3. A circuit arrangement for the suppression of the image frequency response in superheterodyne receivers, comprising a transformer having coaxial primary and secondary windings which have a common low potential terminal connected to ground, a capacitance connected between the high potential terminals of said windings, a resonant circuit including said secondary and a shunt capacitance, and a ferromagnetic core movable relatively to said windings to tune said circuit to any desired signal within a range of frequencies, said primary being wound in the same direction as the secondary and with such varying pitch that at any position of said core the inductance of the series arm of the equivalent π network of said transformer forms with the first-mentioned capacitance connected thereto an image frequency rejector circuit which tracks with the tuning of the resonant circuit.

4. A circuit in accordance with the invention defined in claim 3 wherein the low potential terminals of the transformer are connected to ground through a resistance which serves to reduce the energy dissipation in the image rejector circuit.
